Patented Mar. 13, 1917.

UNITED STATES PATENT OFFICE.

WINFRED MUDGE BROOKS, OF EAST ORANGE, NEW JERSEY, ASSIGNOR TO E. J. BROOKS & CO., OF NEW YORK, N. Y., A CORPORATION OF NEW YORK.

SEAL.

1,219,076.

Specification of Letters Patent. Patented Mar. 13, 1917.

Application filed January 2, 1917. Serial No. 140,277.

To all whom it may concern:

Be it known that I, WINFRED MUDGE BROOKS, a citizen of the United States of America, and a resident of East Orange, 5 in the State of New Jersey, have invented certain new and useful Improvements in Seals, as hereinafter more specifically set forth.

This invention relates to wire seals 10 adapted to be fastened and sealed by hand and of a character that any attempt to tamper therewith will result in fracture thereof.

The object of this invention is to provide 15 a simple seal of the character described with certain novel features hereinafter more fully described for improving its security and to render its proper manipulation in sealing simple and natural.

20 One sheet of drawings accompanies this specification as part thereof, in which like reference characters denote like parts throughout.

Referring to the drawings, Figure 1 25 shows a side view of one type of the improved seal unsealed; Figs. 2 and 3 show front and back views respectively of the same seal; Fig. 4 shows a side view of the seal sealed; Fig. 5 shows the opposite side 30 of the same seal; Fig. 6 shows a side view of a portion of a preferred type preliminary to sealing and Fig. 7 shows a side view of a portion of another type sealed.

The seal ready for use is shown in Figs. 35 1, 2 and 3 and consists of a piece of suitable wire *a* having a substantially tubular coil *b* *b*¹ or *b*² at one end disposed at an angle therewith, said coil terminating at its outer end in a catch *e*. A portion of 40 the wire *a* is flattened as at *g* in a plane substantially perpendicular to that of the axis of the coil *b*. This flattening precludes the bending of the part *g* in any direction other than backward and forward with regard to said tubular coil *b*. A portion *f* 45 of the wire *a* may be suitably embossed with the user's name etc. and the portions *f* and *g* with the short adjacent and intervening portions of the wire *a* constitute what may be termed the loop-forming part of the seal. A stop *c* is provided as a terminus of said 50 loop-forming part and the wire beyond denoted *d* may be termed the sealing part, being provided with transverse cut nicks *v* 55 in the side opposite the catch end of the

tubular coil *b*. Said tubular coil is preferably bent at an acute angle with the loop-forming part (*b*¹ Fig. 6) or may be made conical with the larger end outward with the catch (*b*² Fig. 7) either of which forms 60 naturally induces the introduction of the sealing part *d* into the outer rather than the inner end of the coil.

The tubular coil *b*, *b*¹, *b*² makes it impossible to withdraw the sealing part after 65 same has been inserted through and bent back over said coil without a full straightening of the part which is rendered impossible by the weakening nicks *v*. The flattening of the seal at *g* as described and 70 the particular forming of the tubular coils as *b*¹ in Fig. 6 and *b*² in Fig. 7 make it impossible to bend the loop and insert the sealing part *d* into the coil in any other than the proper manner viz: through the 75 outer or catch end of the coil.

In operation the seal is looped through the staples or other locking means and the sealing part *d* inserted through the outer or catch end of the tubular coil up to the 80 stop *c*. Its end then protruding from the inner end of the coil is bent back and caught under the catch *e* which protects it from accidental displacement.

Having thus fully described my invention, I claim:

1. A wire seal comprising a loop-forming part, a tubular coil angularly disposed at one end thereof having a catch at its outer end, a stop near the other end of said loop-forming part, a sealing part beyond said stop adapted to be passed through said tubular part, bent back and caught under said catch and means for preventing the unbending of said sealing part. 95

2. A wire seal comprising a loop-forming part, a substantially tubular coil angularly disposed at one end thereof, a catch at the outer end of said coil, a flattened portion of the wire in said loop-forming part flattened in a plane substantially perpendicular to that of the axis of said tubular coil, a stop near the other end of said loop-forming part and a part beyond said catch provided with transverse cut nicks in the 100 face opposite the outer or catch end of said coil. 105

3. A wire seal comprising a loop-forming part, a substantially tubular coil angularly disposed at one end thereof, a catch at the 110

outer end of said coil, a stop near the other end of said loop-forming part, a continuation of the wire beyond said stop, transverse nicks cut therein on the side opposite 5 the catch end of the tubular coil, means for causing said loop-forming part to bend only in a plane of the axis of said tubular coil and means for accommodating the outer or catch end of said tubular coil to the 10 ready ingress of said nicked part which is adapted to be passed therethrough up to the stop, bent back over the coil and caught under the catch.

4. A wire seal comprising a loop-forming 15 part, a substantially tubular coil at one end

thereof bent back to form an acute angle therewith, a catch at the outer end of said coil, a flattened portion of the loop-forming part flattened in a plane perpendicular to that of the axis of said coil, a stop near 20 the other end of said loop-forming part, a continuation of the wire beyond said stop, transverse nicks cut into the face of said continuation opposite the catch or outer end of said coil, all substantially as herein- 25 before specified.

WINFRED MUDGE BROOKS.
